UNITED STATES PATENT OFFICE.

PAUL I. MURRILL, OF NEW YORK, N. Y., ASSIGNEE TO REVERE RUBBER COMPANY, A CORPORATION OF RHODE ISLAND.

APPARATUS FOR PRODUCING VULCANIZED ARTICLES.

1,161,951.

Specification of Letters Patent. Patented Nov. 30, 1915.

Application filed March 26, 1915. Serial No. 17,063.

To all whom it may concern:

Be it known that I, PAUL I. MURRILL, a citizen of the United States, residing in the city of New York, county and State of New York, have invented certain new and useful Improvements in Apparatus for Producing Vulcanized Articles, of which the following is a full, clear, and exact description.

This invention relates to apparatus for forming vulcanizable articles of rubber and similar materials and such apparatus as those employed in carrying out the process of dipping and drying the articles on the forms in a closed chamber under the influence of suitable drying conditions or drying medium.

The object of my invention is to provide an improved apparatus for carrying out the process above mentioned, which apparatus is simple in construction, compact in arrangement, and easy of operation, and is adapted to produce the best results with a minimum waste of the solvent, drying medium or heat. In the disclosure of this form of the invention, I do not wish to be understood as being limited to the precise details and arrangement of parts, since this invention is intended to illustrate the type of apparatus in which variations may be made without departing from the general principle thereof. For a detailed description of this form of my invention, reference may be had to the following specification and to the accompanying drawings forming a part thereof in which:

Figure 1 is a side elevation of my improved apparatus; and Fig. 2 is a vertical sectional view.

Referring to Figs. 1 and 2, the numeral 1 indicates four uprights and the numeral 2 the cross-bars which with the guides 3 and the struts 4 constitute a frame for the apparatus. The numeral 5 indicates suitable I-beams on which are carried T-rails 6. The rails 6 are adapted to form a track for a car 7 in the form of a tafik for containing the rubber solution. The numeral 8 indicates a casing having no permanent bottom and with which is connected an eduction pipe 9. The casing 8 is rigidly supported in any suitable manner on the cross-bars 2. The numeral 10 indicates a hollow platen supported at both sides by projecting trunnions 11 which are also connected with a steam supply pipe 12. The trunnions 11

pass through suitable bearings 13 which carry the yokes 14 which slidably engage the ribs 15 on the uprights 3. The trunnion 11 at the right hand side of the platen 10 (Fig. 2) is provided with a projecting shaft 16 on which is fixed a toothed wheel 17 adapted to be engaged by a pawl 18 pivoted on the upper end of the yoke 14. The yokes 14 are provided with ears 19 to which may be attached cords or cables 20 for raising and lowering the platens 10. These cables pass over two wheels or drums 21 to which the inner ends of the cables 20 are fastened. The drums are supported on the shaft 22 having at one end a sprocket wheel 23 over which passes the sprocket chain 24. This sprocket chain also engages a sprocket wheel 25 which carries a hand-crank 26.

In utilizing this device the same is manipulated as follows: The requisite hollow forms for the articles to be made being placed on the platen 10, the tank 7 is filled with a rubber solution or other material to be used. The forms are then inverted by manipulating the toothed wheel 17 and the pawl 18 so that the forms may be inserted downward into the rubber or other solution. The crank handle 26 is then turned, the forms thereby being withdrawn from the solution and the pawl 18 disengaged from the toothed wheel 17 to allow the forms to be reversed and placed in an upright position, as indicated in dotted lines in Fig. 2. The platen 10 and the forms thereon are further raised until the platen closes the bottom of the casing 8. Steam is then admitted through the pipe 12 to the platen 10 and to the interior of the forms. A vacuum is then produced within the casing 8 through the pipe 9. After a sufficient amount of evaporation has taken place from the material on the forms, the vacuum is discontinued, the platen is again lowered and turned and the forms placed in the rubber solution. This is a preferred sequence of steps and is repeated a number of times to give the necessary thickness to the article being produced. However, I do not wish to be limited to said sequence of steps, for the same may be varied as to order or duration, according to particular requirement.

In Fig. 2 I have shown inclosed walls 27 which may be employed if it is desired to keep the articles free from dust and contact with air currents during the transfer of

the forms from the dipping tank to the vacuum chamber.

What I claim and desire to protect by Letters Patent is:

- 5 1. A dipping and drying apparatus comprising a chamber adapted to contain the material of which articles are to be made, a vacuum chamber, a support upon which forms for said articles are carried, and means for transferring said support to dip said forms into said material and for introducing the same into said vacuum chamber.
- 10 2. A dipping and drying apparatus comprising a chamber adapted to contain the material of which articles are to be made, a vacuum chamber, a support upon which forms for said articles are carried, means carried by said support for heating said forms, and means for transferring said support to dip said forms into said material and for introducing the same into said vacuum chamber.
- 15 3. A dipping and drying apparatus comprising a chamber adapted to contain the material of which articles are to be made, a vacuum chamber, a platen upon which
- 20
- 25

forms for said articles are carried, means carried by said platen for heating said forms, said platen being adapted to close the opening into said vacuum chamber, and means for transferring said platen to dip said forms into said material and for introducing the same into said vacuum chamber.

4. A dipping and drying apparatus comprising a chamber adapted to contain the material of which articles are to be made, a vacuum chamber, a hollow platen upon which hollow forms for said articles are carried, a flexible pipe connection connected with said platen, said platen being adapted to close the opening into said vacuum chamber, and means for transferring said platen to dip said forms into said material and for introducing the same into said vacuum chamber.

Signed at New York, county of New York, State of New York, this 23rd day of March 1915.

PAUL I. MURRILL.
